UNITED STATES PATENT OFFICE.

ANNIE S. GRIGGS, OF SANTA BARBARA, CALIFORNIA.

COMBINATION BOOKHOLDER AND TABLE.

Application filed May 5, 1926. Serial No. 106,988.

This invention is a combined book holder and table for the use of invalids, and this application is a new application covering the same invention as originally described and claimed in the application filed in the 5 United States Patent Office January 20, 1922, under Serial Number 530,509, and allowed May 11, 1922. The object is to provide a simple and practical adjustable arti- 10 cle of this kind.

In the drawings:

Figure 1 is a plan view.

Figure 2 is a side elevation, showing the device adapted for use as a table.

15 Figure 3 is a side elevation, showing the device adapted for use as a book holder or support.

Figure 4 is a front elevation.

20 Figure 5 is a detail of the extensible supporting arm.

The invention consists of a table board 1, having a base strip 2 hinged at 3 along the back edge. Another book holding strip 4, having an angular recess 5 cut along its upper and forward corner, is hinged at 6 to the base strip 2 so that the book strip will fold and lock in upright position upon the base strip, the angular recess 5 fitting over the corner of the base strip. A slotted bar

25 7, slotted at 8 and having inset ends 9 is secured by screws 10 through these ends to a side edge of the table board 1. An adjusting brace 11 has one end pivoted at 12 to the book strip 4, and the opposite end lock- 30 ily engages the slot 8 through the medium of a thumb screw 13. An ordinary extensible arm 14 is secured at one end to the table board 1 by means of the bracket rod 15, the latter being screwed at 16 to the under side of the board. The opposite end of 35 the arm 14 is similarly secured to the bed 17 by means of the rod 18, attached by bolts or screws 19. An adjustable supporting leg 20 is hinged at 21 to the under side of the 40 table board 1, and thus adapted to fold up

out of the way when not in use. This leg 20 has a slot 22 in which is slidably mounted an extension 23 carrying the foot 24. A thumb screw clamp 25 enables the locking of the extension 23 at any desired point. A 50 recess 26 is cut in the under side of the board 1 to receive the thumb screw 25 when the leg 20 is folded up. The operation and use of the device is obvious.

While I have herein described a certain 55 specific method of constructing and assembling the elements of my invention, it is understood that same may be varied in minor details, not departing from the spirit of my invention as defined in the appended claims. 60

I claim:

1. A book holder and table for beds, comprising a table board; a base strip hinged to the back edge thereof; a book holding strip hinged in turn to the base strip; a 65 slotted bar secured to a side edge of the table board; an adjusting brace pivoted to the book strip at one end while the opposite end releasably engages the said slotted bar; an extensible arm secured at one end to the 70 table board, the opposite end being adapted for securing to a bedstead; and an adjustable supporting leg mounted under the table board.

2. A book holder and table for beds, comprising a book strip having an angular recess along one corner; a base strip hinged to the recessed edge of the book strip so that the former will fold and lock in upright position upon the base strip; a table 75 board hinged to the base strip and adapted to turn to the same side thereof as the book strip; an adjustable brace for locking the book strip; base strip and table board in angular relation; an extensible arm for extensiblly securing the table board to a bedstead; and an adjustable and folding supporting leg for supporting the table board upon the bed. 80 85
